UNITED STATES PATENT OFFICE.

WILLIAM H. POWELL, OF EAST ORANGE, NEW JERSEY, ASSIGNOR TO CROCKER-WHEELER COMPANY, OF AMPERE, NEW JERSEY, A CORPORATION OF NEW JERSEY.

RHEOSTAT.

SPECIFICATION forming part of Letters Patent No. 783,979, dated February 28, 1905.

Application filed October 24, 1904. Serial No. 229,739.

To all whom it may concern:

Be it known that I, WILLIAM H. POWELL, a citizen of the United States of America, and a resident of East Orange, county of Essex, and State of New Jersey, have invented certain new and useful Improvements in Rheostats, of which the following is a specification.

This invention relates to the manner of arranging and combining the resistance-conductor and contact-blocks and the manner of their support to form a substantial compact and effective rheostat of few parts and simple construction. The form illustrated is designed for hand operation and for use as a starting-rheostat for electric motors, as the construction claimed is especially well adapted to this purpose, wherein a considerable mass is requisite to absorb the heat generated upon the operation of the rheostat; but special provision is made for the radiation and dispersion of the heat is of little importance, owing to the fact that a considerable interval of time elapses between successive operations.

In the accompanying sheet of drawings, which form a part of this application, Figure 1 is a side view of a rheostat embodying my invention. Fig. 2 is a top view with the upper plate broken away. Fig. 3 is a detail showing a form of connection between an intermediate contact-bar and the resistance-ribbon.

A conducting-ribbon A, which may be of thin copper, iron, German silver, or other conducting material, is coated with any suitable insulating material. A mixture of whiting, glue, and bichromate of potash has been found well adapted to this purpose, as it can be applied in liquid form, hardens in the light, and will withstand a reasonably-high temperature. One end of the ribbon is riveted to a post or block B and is coiled around this block in a flat coil or spiral, the post forming the center of the spiral. This post forms one of the terminals of the rheostat, one end being threaded and provided with a nut b for this purpose. The other end of the post is the final contact on which the circuit is closed.

At intervals of several turns of the conducting-ribbon metal contact-blocks C, preferably copper or brass, are inserted between the convolutions of the ribbon and form the intermediate contacts of the rheostat. These blocks are disposed in a line, preferably slightly curved and approximately radial to the coil with the central post of the coil at one end of the line. One of the convolutions adjacent to each block is bared of insulation, so as to make electrical contact between the ribbon and block. As preferably constructed, both the conducting-ribbon and the contact-blocks are much thinner in proportion than it has been practicable to illustrate them in Fig. 2, and, as shown in Fig. 3, the connection between the ribbon and contact-block is conveniently made by obliquely slitting the edges of the block and passing the ribbon through the slits. The outer contact-block D of the line of blocks to which the outer end of the coil of ribbon is attached is thicker than the intermediate blocks, and the end at which contact is made has a separate piece d screwed to the block, so that it can be conveniently renewed, since the circuit is broken at this block.

The spirally-coiled conducting-ribbon is placed on a slate slab E, forming the under slate of the rheostat. The terminal end of the central post projects through a hole in this slab, and the lower ends of the intermediate contact-blocks rest against the slab. A slate slab F, conveniently of the same size, forms the upper side or face of the rheostat, and a curved slot f is cut through this slab, the outline of the slot in that part of the slab which is broken away in Fig. 2 being indicated by dotted lines. The contacting ends of the contact-blocks project through this slot, and the spaces between the projecting ends are filled with insulation G. A movable contact-arm H is mounted above the front slab of the rheostat and has a movement parallel to the surface of the rheostat and the face of the inclosed resistance-coil and over the projecting ends of the contact-blocks. It is pivoted to a pin I, which

forms the other terminal of the rheostat, one end being threaded and provided with a nut *i* for this purpose. This pin is supported by the slate slabs and eccentric to the axis of the 5 spirally-coiled ribbon, so that the contacting part of the arm can be moved over a path across the convolutions of the ribbon and contact with the projecting ends of the contact-blocks, which are placed between different convolutions of the ribbon. The arm is returned to the open position in which it is illustrated by a spring *K* and rests against a buffer *L*. The contacting part rests on a dead-block *N*, which is attached to the upper slate. 10 When the rheostat is operated to close the circuit to a motor, the arm is first moved into contact with the block *D* and the circuit is established from the terminal *I* through the arm, the block *D*, the coiled resistance-ribbon 15 from the outer to the inner end of the central part, forming the terminal *B*. Continued movement of the arm over the intermediate contact-blocks cuts out resistance in sections, the outer coils being first cut out and lastly 20 the inner coils, the circuit being finally established from the terminal *I* through the arm to the terminal *B*, and the arm is held in place by a holding-magnet *P*. 25 In order to avoid too great a surge of current at the moment of operation from any contact to the next, the included resistance which is thereby cut out should always be within a certain percentage of the resistance remaining in the circuit. If, on the other hand, 30 the steps are much smaller than is really required in any part, there will be an undue multiplication of contacts. To meet both conditions, the actual resistance of the sections which are first cut out should be much greater than 35 the resistance of the sections which are last cut out of circuit and are sufficiently approximated by an arithmetical ratio. This condition results from the construction set forth, 40 without unequal spacing of the contact-blocks 45 traversed by the contact-arm by reason of the decreasing length of successive convolutions

of the spiral coil, to which the contact-blocks are directly connected.

What I claim as new, and desire to secure by Letters Patent of the United States, is— 50

1. In a rheostat, the combination of a resistance element consisting of a spirally-coiled conducting-ribbon, a movable contact member adapted to be moved above and parallel to the flat face of the spiral coil, and contact-blocks 55 disposed in the path of the movable contact member and contacting with different convolutions of the ribbon, substantially as described.

2. In a rheostat the combination of a resistance element consisting of a spirally-coiled 60 conducting-ribbon, a contact-arm adapted to be moved above and parallel to the flat face of the spiral coil, and contact-blocks disposed in the path of the contact-arm and contacting with different convolutions of the ribbon, sub- 65 substantially as described.

3. In a rheostat the combination of a resistance element consisting of a spirally-coiled 70 conducting-ribbon, a contact-arm adapted to be moved above and parallel to the flat face of the spiral coil and eccentric thereto, and contact-blocks disposed in the path of the contact-arm and contacting with the different convolutions of the ribbon, substantially as described.

4. In a rheostat, the combination of rheostat- 75 terminals, a resistance element consisting of a coiled conducting-ribbon connected at the inner end of the coil to one of the terminals, a movable contact member adapted to be moved above and parallel to the flat face of the spiral 80 coil, contact-blocks disposed in the path of the movable contact member and contacting with the different convolutions of the ribbon, and connections through the movable contact member to the other terminal, substantially as de- 85 scribed.

Signed by me at East Orange, New Jersey, this 22d day of October, 1904.

WILLIAM H. POWELL.
